(57) CLAIM

The ornamental design for a ball cap having indicia comprising a basketball skin, as shown and described.

DESCRIPTION

FIG. 1 is a front, right perspective view of a ball cap having indicia comprising a basketball skin;

FIG. 2 is a front elevation view thereof;

FIG. 3 is a left side elevation view thereof;

FIG. 4 is a right side elevation view thereof; and,

FIG. 5 is a top plan view thereof.

A characteristic feature of the design resides in the indicia on the front of the cap that comprises a basketball skin and the texture thereof.
